SEALING DOOR

Robert F. White, 1801 Princeton St., Alexandria, La.
Filed Sept. 22, 1961, Ser. No. 139,968
18 Claims. (Cl. 20—24)

This invention relates to sealing, or safety, doors for use on railway cars, such as boxcars or merchandise cars, grain elevators, transport trucks, storage bins, warehouses, or on any enclosure which it is desired to make burglar proof, air or liquid proof.

It is common practice when necessary to seal a storage compartment of some kind to either erect a wooden or paper door, or to put sealing strips around the edges of the normal door. Sealing is required when the car, truck or building is to contain a flowable product, such as grain, to prevent escape of the product, to prevent air and moisture from reaching the product, or to prevent escape of chemicals used in fumigating the product. Many structures designed to be permanent installations have been proposed, but, due to inconvenience of operation, improper sealing qualities, or excessive cost, these have not come into common use.

The general object of the present invention is to provide a sealing door for permanent installation at a doorway in an enclosure which will provide a positive seal around the door frame and floor, or sill, and can be operated easily by one man.

A more specific object is to provide a sealing door which can be locked and unlocked from outside the enclosure to ensure safety of the contents.

A further object is the provision of a door of this type composed of a plurality of relatively movable sections which are designed for pressure contact with one another and with a door frame to provide a leak-proof seal.

Yet another object of the invention is to provide a sealing door which can be moved from its door-sealing position and locked in an inoperative position where it will not interfere with the normal operation of the car, truck, etc. on which it is mounted.

Still another object is to provide a door structure which will be extremely rugged, so that little maintenance will be necessary and the door will last as long as the vehicle which carries it.

Other objects of the invention will become apparent from the following description of one practical embodiment thereof, when taken in conjunction with the drawings which accompany, and form part of, this specification.

In the drawings:

FIGURE 1 is a side elevation of a freight car with the standard door broken away to show the sealing door inside the door opening;

FIGURE 2 is an enlarged fragmentary vertical section through the car, illustrating the sealing door structure in elevation as viewed from inside the car with the door in sealing position;

FIGURE 3 is a view similar to FIGURE 2 but with one of the door units removed from sealing position;

FIGURE 4 is a horizontal section through one wall of the car at the door opening with the sealing door in locked sealing position, and is taken on the line 4—4 of FIGURE 2;

FIGURE 5 is a vertical section through the door and adjacent car portions, taken on the line 5—5 of FIGURE 2;

FIGURE 6 is an exploded perspective view of the elements making up the door;

FIGURE 7 is a fragmentary vertical section taken on the line 7—7 of FIGURE 3, showing how the door proper is hung and biased vertically for sealing;

2

FIGURE 8 is a horizontal section taken on the line 8—8 of FIGURE 3, illustrating the bottom pressure applying mechanism in locked position, and is taken on the line 8—8 of FIGURE 3; and

5 FIGURE 9 is a horizontal section similar to FIGURE 8 with the door in unlocked condition and moved partially from door-blocking position.

In general, the invention contemplates the provision of a door of skeletal construction which is movable to and from doorway closing position, and a carrier, also movable to and from the doorway, which slidably mounts closure members for the open-frame door. The carrier is adapted to apply sealing pressure to the door proper, and serves also as a bearing element for the closure members, so that they may be placed in pressure contact with the door.

As mentioned above, the door of the present invention is suitable for use as a sealing door for many types of enclosures. For purposes of disclosure, it is illustrated 20 in conjunction with a boxcar.

Referring to the drawings in detail, a boxcar 1 is shown having sidewalls 2, in at least one of which there is a doorway 3. A conventional door 4 is mounted in upper and lower guide tracks 5 and 6 carried by the car outer 25 wall for sliding movement along the car wall to cover and uncover the doorway 3. The car has a roof 7 and a floor 8. This much of the structure is conventional, and may vary in different installations.

The sealing door consists of a skeletal door 9 mounted 30 for sliding movement along an overhead track 10, fixed to the car roof. The track is adjacent the door opening so that when the door is abreast the doorway, it is in close proximity to the door jambs 11 and lintel 12. A second track 13, parallel to track 10, supports a carrier frame 35 14 so that the carrier frame can be moved independently of, or with, the door 9. The paths of the door and carrier frame are closely adjacent, and the carrier frame and door are practically in surface contact. The carrier frame, in turn, slidably supports the panel closure members 15 and 16, which allows the closure members to move over the door to close the openings therein and to move away from door-closing position.

Door 9 is rectangular in shape, and of such size that 45 its edges overlap the door jambs 11 and lintel 12. The door is formed of vertical side stiles 17, top and bottom bridge members 18 and 19, and a central bridge member 20. An upper access opening 21 is framed by the top and central bridge members and the side stiles, and a lower access opening 22 is framed by the stiles and the 50 central and bottom bridge members. A strip 23 of resilient sealing material is placed along the stiles and top bridge members for sealing contact with the jambs and lintel of the doorway, as will be described. A strip 24 of sealing material is inserted in a groove 25 in the door bottom for contact with the car floor.

The track 10, which supports the door is of rectangular cross-section with its bottom 26 mounted against the car roof. The bottom of the track has a central slot 27, which 55 divides the bottom into two, spaced rails 28. Pairs of slides 29 are mounted in the track to move along the rails, the slides of each pair being held in spaced relation by a connecting pin 30. Cam links 31 are pivotally mounted on pins 30 and have their lower ends pivotally connected by pin 32 to a channel 33, screwed to the top of the door. The cam links are connected by a rod 34 so that they will move in unison. The upper ends 35 of the cam links project beyond the tops of the slides 29 for bearing contact with the bottom 26 of track 10, when the links are swung about pivot pins 32 toward a vertical position. Continued pivotal movement of the links after the upper ends contact the track bottom, will exert a down-

ward force upon the door, pressing the strip 24 into tight sealing contact with the floor of the car. Links 31 are operated by means of a lever 36 which is pivotally mounted by pin 37 between the side walls of channel 33 at one edge of the door. The pivot is spaced from one end of the lever to provide a force arm 38. A link 39 interconnects the end of arm 38 and the adjacent cam link 31. Raising and lowering of the operating arm 40 of lever 36 will rock the cam links to lift and depress the door 9. The edge of the door adjacent the pivot 37 is grooved, as at 41, to permit the operating arm 40 of lever 36 to seat below the edge surface of the door. An eye 42 is mounted in groove 41 and the operating arm of the lever has a slot 43 to fit over the eye. A locking pin 44 is inserted through the eye to hold the lever in place in the groove and the door tightly sealed against the floor.

The carrier frame 14 is open, consisting simply of vertical end members 45, a top member 46 and a bottom member 47. Roller carriages 48 carrying rollers 49 are mounted on the top member. The rollers ride on rails 50 at the underside of track 13. Track 13 is identical in construction to track 10. The carrier frame has two intermediate horizontal rails 51 and 52 which extend between the end members 45. Each of these is composed of a pair of track members 53 similar to tracks 10 and 14 arranged back to back. This places the slot 54 of the top track upward and the slot 54 of the bottom track downward. These tracks support the panel closure members, as will be described.

At the top and bottom of the frame carrier there are clamping jacks 55. These are adjacent one end of the frame, that end which is opposite the door way when the frame is in locking position. Each jack includes a track section 56, fixed to the bottom member 47 of the frame carrier, and a similar track section 57, spaced from the section 56 and tied to it by means of a strap 58, extending diagonally between the track sections and pivoted at one end by a pin 59 to the fixed track section 56 and at the other end by pin 60 to the movable track section 57. The two track sections are arranged so that their sides having slots 61 are face to face, and the strap 58 projects through the slots. Cam links 62, similar to cam links 31, have their ends pivoted at 63 to the fixed track section 56. Their opposite ends are pivotally connected to slides 64 which ride on the rails 65 of the movable track section. The links project beyond the slides to form bearing ends for contact with the bottom of track section 57. Links 62 are interconnected by tie rod 66.

Links 62 are caused to rock about their pivots 63 by means of an operating mechanism 70. This includes a vertical shaft 67 journaled in bearing brackets secured to one of the vertical end members 45 of the carrier frame. Shaft 67 has lever arms 68 fixed to its ends for rotation with it. Links 69 interconnect the free ends of lever arms 68 and the adjacent cam links 62, so that rotation of shaft 67 will cause rocking movement of the cam links. A lever 70 is connected to shaft 67 to form a handle for rotating the shaft. The handle has a base portion 71 fixed to the shaft, and an outer portion 72 connected to the base portion by a horizontal pivot 73 to allow the major portion of the handle to swing downwardly and lie adjacent the shaft when not being used. Brackets 74 are fastened to the car roof to form stops to limit the outward movement of the movable member 57 of the upper jack assembly 55. A similar bracket 75 is fixed to the car floor to form an abutment for one end of the lower jack member 57. The other end of the lower member 57 carries a pivoted latch 76 for engagement with a hook 77 on the door frame to hold the member 57 against outward movement when in locking position and a hook 78 on the opposite jamb of the door frame when the carrier frame is removed from the door. With this arrangement, rotation of shaft 67 will rock cam links 62 to bring the track members 57 into contact with the

brackets 74 and 75 and pull latch 76 tight against hook 77. As the outward movement of the members 57 is then stopped, further rocking movement of links 62 exerts a force against the frame carrier, forcing it against the door 9 and pressing the door into sealing relation with the door jambs and lintel.

The upper panel closure 15 has a panel 79 of somewhat larger area than the upper access opening 21 in door 9 to overlie that opening and close it. A sealing strip 80 10 is mounted on the face of the panel around the perimeter for pressure contact with door 9 about the opening 21. Brackets 81 are fixed to the inner face of panel 79, and these carry rollers 82 which ride in the track members 53 forming the rails 51 and 52 of the frame carrier. This 15 mounts the panel on the carrier for sliding movement along the tracks 53.

Clamping jacks 83 are mounted at top and bottom of the panel 79. These consist of horizontal track sections 84, fixed to the panel, and track sections 85, mounted upon support straps 86. Straps 86 have brackets 87, similar to brackets 81, fastened to them, and these brackets also carry rollers 88 mounted in the tracks 53. Thus, both the panel and straps 86 have rolling support on the tracks. The track sections 84 and 85 are interconnected by cam links 89 so that the entire assembly will move as a unit along tracks 53. Cam links 89 are pivotally connected to track sections 84 by pins 90. The opposite ends of links 89 carry grooved rollers 91 for bearing contact against the bases of track sections 85. The rollers are held against movement longitudinally of track sections 85 by means of pins 92 which extend through the side flanges of the track sections and lie in the grooves 93 of rollers 91. This permits some movement of the rollers transversely of the track sections.

The cam links 89 are rocked about their pivots 90 by means of rods 94, connected to the track sections and to lever arms 95 at the top and bottom of a control shaft 96. The shaft is journaled in bearings 97 carried by the panel 79, and is rotated by an operating arm 98 rigidly mounted on the shaft. The outer end of operating arm 98 is slotted, as at 99, and a nut 100 is slidably mounted in the slot. Nut 100 is threaded upon a screw 101, rotatably supported in a plate 102 screwed to the inner face of the panel 79. The screw 101 projects outwardly into an opening 103 in the panel, and this end 104 is shaped to receive an operating key 105 having a mating end 106. When the key is inserted in opening 103, fitted upon the screw end, and rotated, nut 100 will be caused to move along the screw length, thus rotating control shaft 96 and rocking cam links 89 about their pivots 90. This will cause track section 85 to move outwardly taking up all transverse play of rollers 88 in tracks 53. Additional movement of the cam links will result in outward pressure being put upon panel 79 to bring it into sealing relation with the door 9.

Lower panel closure member 16 is identical in all respects with the upper one, except insofar as the operating arm is concerned. Therefore, the same reference numbers used in connection with the closure member 15 have been used on closure member 16 with the addition of a prime.

Operating arm 107 of the clamping jacks 83' of panel closure member 16 has an aperture 108 to receive a locking pin 109 which also passes through the legs of 65 a bifurcated bracket 110 carried by the panel 79'. Thus, when the lever is moved to panel-locking position against the panel 79', the end of lever 107 will be between the legs of bracket 110 and locking pin 109 can be inserted to hold the lever against movement.

When the sealing door described has been installed in a freight car, and it is desired to seal the doorway, door 9 will be pulled along its track 10 to a position overlying the door opening. When the door is in position, operating lever 36 will be pulled down causing cam links 31 to rock about their pivots 32 and force the

5

door downward into sealing contact with the car floor. Locking pin 44 will be placed through the lever slot 43 and eye 42 to hold the lever in clamping position. Carrier frame 14 will be moved along its track 13 to a position in back of door 9. A latch 111 is operated to hold the frame carrier against movement along its track. This latch may have a latch arm 112 pivoted, at 113, to a bracket 114 carried by the movable track section 57 of the upper clamping jack of the carrier frame. The latch arm may engage an opening 115 in one of the brackets 74. When the carrier frame is in position, lever 70 will be operated to cause the clamping jacks 55 to force the carrier frame against the door 9, and the door 9 against the door frame. This will completely seal the edges of the door.

The operator can then leave the car through one of the access openings 21 or 22. From the outside of the car the closure panel member 16 can be slid along its tracks to its position over the lower access opening 22. The lever 107 will be operated to clamp the panel in place, and the locking pin 109 will be inserted to hold the lever in locked position. Closure panel member 15 will then be moved along its rail 51 to cover the access opening 21. Key 105 will be inserted in opening 103 to engage end 104 of screw 101. As the key is rotated the clamping jacks 83 will operate to bring panel 79 into sealing contact with the face of door 9. The doorway will now be completely sealed, and cannot be opened except by an authorized person having a proper key.

When the door is to be opened, a reverse procedure will be used. Key 105 will be used to release closure panel member 15, which can be slid back to allow access to the car. Closure panel member 16 can be released and moved back, and the carrier frame can be unlocked and rolled back out of the way. Finally, the door 9 can be released and moved away from the doorway. If desired, all of the parts, except closure panel member 15, can be locked in their inoperative positions to hold them stationary when not in use. As the closure panel member 15 is on the carrier frame it cannot move in front of the doorway.

While in the above one practical embodiment of the invention has been disclosed, it will be understood that the structural details described and shown are merely by way of example, and the invention may take other forms within the scope of the appended claims.

What is claimed is:

1. A sealing door for an enclosure having a floor and a sidewall with a doorway therein comprising, a door supported upon the enclosure for sliding movement along a path to and from doorway closing position, a frame carrier supported upon the enclosure for sliding movement parallel to and adjacent the path of movement of the door, fixed abutments on the enclosure, and clamping jacks mounted on the frame carrier for engagement with the abutments to exert pressure between the abutments and the frame carrier to press the frame carrier against the door and the door into sealing contact with the enclosure about the doorway.

2. A sealing door as claimed in claim 1 wherein, the means supporting the door is a track, and there are means to bear against the track and exert downward pressure on the door to press the door into sealing contact with the enclosure floor.

3. A sealing door as claimed in claim 2 wherein, there is a sealing strip around the door intermediate the door and the enclosure wall around the doorway, and a sealing strip along the bottom of the door.

4. A sealing door as claimed in claim 1 wherein, the door has at least one access opening therein, and there is a closure panel member mounted on the carrier frame for sliding movement thereon for moving the panel closure member to and from a position overlying the access opening in the door, and means for clamping

the closure panel member in sealing relation with the door about the access opening.

5. A sealing door as claimed in claim 4 wherein, the means for clamping the closure panel member is accessible from outside the enclosure.

6. A sealing door as claimed in claim 5 wherein, there is a removable key for operating the means for clamping the closure panel member.

7. A sealing door for an enclosure having a floor and a sidewall with a doorway therein comprising, a pair of parallel overhead closely spaced tracks supported from the enclosure parallel with the enclosure sidewall and extending across the doorway and to a point removed from the doorway, a door hung from the one of the said pair of tracks adjacent the sidewall for sliding movement to and from positions overlying the doorway, a frame carrier hung from the other one of said pair of tracks of sliding movement therealong, fixed abutments on the enclosure parallel to the tracks and on the side of the tracks remote from the enclosure wall, and clamping jacks mounted on the frame carrier intermediate the frame carrier and the abutments, and means to operate the clamping jacks to exert pressure between the abutments and the frame carrier to press the frame carrier against the door and the door into sealing relation with the enclosure wall about the doorway.

8. A sealing door as claimed in claim 7 wherein, the clamping jacks include a section fixed to the frame carrier and a movable section for engagement with the abutment, with cam links interconnecting the sections and means to rock the cam links to increase the distance between the jack sections.

9. A sealing door as claimed in claim 7 wherein, there are means supporting the door from the track including rockable means for raising and lowering the door relative to the track, whereby the door may be lowered into sealing contact with the enclosure floor.

10. A sealing door as claimed in claim 9 wherein there are means to actuate the rockable means, and means to lock the actuating means to hold the door in sealing relation with the enclosure floor.

11. A sealing door as claimed in claim 7 wherein, the door has at least one access opening therein, the frame carrier has a horizontal rail, a closure panel member is mounted on the rail for sliding movement therealong to and from a position overlying the access opening in the door, and the closure panel member carries clamping jacks to press the closure panel member into sealing relation with the door about the access opening.

12. A sealing door as claimed in claim 11 wherein, the means for clamping the closure panel member is accessible from outside the enclosure.

13. A sealing door as claimed in claim 12 wherein, there is a removable key for operating the means for clamping the closure panel member.

14. A sealing door for an enclosure having a floor and a sidewall with a doorway therein comprising, a pair of parallel overhead closely spaced tracks supported from the enclosure parallel with the enclosure sidewall and extending across the doorway and to a point removed from the doorway, a door hung from the one of the said pair of tracks adjacent the sidewall for sliding movement to and from positions overlying the doorway, means to press the door downwardly into sealing relation with the enclosure floor, the door having upper and lower access openings therein, a frame carrier hung from the other one of said pair of tracks for sliding movement therealong, fixed abutments on the enclosure parallel to the tracks and on the side of the tracks remote from the enclosure sidewall, clamping jacks mounted on the frame carrier intermediate the frame carrier and the abutments, means to operate the clamping jacks to exert pressure between the abutments and the frame carrier to press the frame carrier against the door and the door into sealing relation with the enclosure wall about the doorway, a pair of

70

75

vertically spaced horizontal rails mounted on the frame carrier, upper and lower closure panel members mounted on the rails for movement to and from positions overlying the upper and lower access openings in the door, and clamping jacks carried by the closure panel members operable to press the respective closure panel members into sealing relation with the door about the respective access openings.

15. A sealing door as claimed in claim 14 wherein each of said clamping jacks includes a track section fixed to the member that carries the jack and a movable track section, the fixed and movable track sections being interconnected by cam links, and means to rock the cam

links to vary the spacing between the fixed and movable track sections.

16. A sealing door as claimed in claim 15 wherein there is means to lock the respective clamping jacks in clamping position.

17. A sealing door as claimed in claim 16 wherein the means to rock the cam links of the clamping jacks of one of the closure panel members is accessible from outside the enclosure.

18. A sealing door as claimed in claim 17 wherein, there is a removable key for operating the means to rock the cam links accessible from outside the enclosure.
